UNITED STATES PATENT OFFICE.

DOMINICK O'DONNELL, OF NEW YORK, N. Y.

HOSIERY.

1,076,603.

Specification of Letters Patent. Patented Oct. 21, 1913.

Application filed October 21, 1912. Serial No. 726,947.

To all whom it may concern:

Be it known that I, DOMINICK O'DONNELL, a citizen of the United States, and a resident of the city of New York, borough 5 of Manhattan, in the county and State of New York, have invented new and useful Improvements in Hosiery, of which the following is a full, clear, and exact description.

The object of the invention is to provide 10 new and useful improvements in knit socks, knit stockings and like knit articles of hosiery whereby such articles can be easily worn and held up in proper position without the use of separate devices such as garters, hose supporters and the like.

In order to accomplish the desired result 15 use is made of two separate elastic bands arranged in the hem or welt at the upper end of the article of hosiery, the ends of the bands being secured to the hem and the ends being spaced apart at the front and rear of the article.

A practical embodiment of the invention 20 is represented in the accompanying drawings forming a part of this specification, in which similar characters of reference indicate corresponding parts in both views.

Figure 1 is a side elevation of a sock provided with the improvement; and Fig. 2 is 25 an enlarged sectional plan view of the same on the line 2—2 of Fig. 1.

The body of the sock, stocking or similar article of hosiery consists of the usual foot and heel portion A and the leg B having a contracted closely woven top portion B' 30 terminating in an integral welt or a hem B². Within the welt or hem B² are arranged two elastic bands C and C' fastened at their ends by stitches D or other fastening means to 35 the welt. The bands C and C' are arranged in the sides of the hem or welt B² and their fastened ends are spaced apart at the front and at the back of the welt.

When the sock or stocking is drawn in 40 position on the wearer's leg the welt or hem B² is expanded and in doing so the elastic bands C and C' are placed under tension to firmly hold the sides of the welt or hem

against the sides of the user's leg thereby 45 sustaining the sock or stocking in position 50 on the leg without the use of hose supporters, garters or like devices.

By providing the elastic bands C, C' only 55 at the sides of the welt the circulation of the blood in the wearer's leg is not seriously interfered with as is the case with garters or elastic bands now generally used and completely encircling the leg. It is understood 60 that the tension of the elastic side bands C and C' is sufficient to hold up the upper ends 65 of the sock or stocking.

It will be noticed that by having the elastic bands C and C' spaced apart at the front no undue pressure is exerted on the tibia of the leg when the improvement is 70 used in a sock. The rear ends of the elastic bands C and C' terminate a distance from the rear seam and consequently do not exert undue pressure on the seam in an inward direction to avoid undue pressure of the seam 75 on the rear of the wearer's leg.

Having thus described my invention, I claim as new and desire to secure by Letters Patent:

A sock substantially as herein described 75 provided with a hem at its upper edge and having within said hem at the opposite sides of the sock elastic strips each of a length less than the semi-circumference of the sock end, the said elastic strips being secured at their 80 ends to the sock and being spaced apart at their front and rear ends, the space between the front ends of the strips being sufficient to receive the tibia of a leg in the use of the sock and the space between the rear ends 85 of the strips being sufficient to avoid interfering with the circulation of the blood at the back of the wearer's leg, all substantially as and for the purposes set forth.

In testimony whereof I have signed my 90 name to this specification in the presence of two subscribing witnesses.

DOMINICK O'DONNELL.
